US00D863257S

(12) **United States Design Patent** (10) **Patent No.:** **US D863,257 S**
(45) **Date of Patent:** **** Oct. 15, 2019**

(54) **MUSIC CONTROL DEVICE**

(71) Applicant: **Dasz Instruments Inc.**, Vancouver (CA)

CN 104021781 A 9/2014
EP 0 268 723 6/1988

(Continued)

(72) Inventor: **Dariusz Bartłomiej Garncarz**, Vancouver (CA)

(73) Assignee: **DASZ INSTRUMENTS INC.**, Vancouver, B.C. (CA)

(**) Term: **15 Years**

(21) Appl. No.: **29/639,967**

(22) Filed: **Mar. 9, 2018**

Related U.S. Application Data

(62) Division of application No. 29/579,960, filed on Oct. 4, 2016, now Pat. No. Des. 815,064.

Primary Examiner — Sheryl Lane

Assistant Examiner — Samantha N Wood

(74) *Attorney, Agent, or Firm* — Knobbe, Martens, Olson and Bear, LLP

CLAIM

The ornamental design for a music control device, as shown and described.

DESCRIPTION

FIG. 1 is a perspective view of a music control device according to the design, the music control device of FIG. 1 including a wide module and three narrow modules; FIG. 2 is a top view of the music control device of FIG. 1; FIG. 3 is a perspective view of a music control device according to a variant of the design, the music control device of FIG. 3 including a wide module and at least one narrow module of the music control device of FIG. 1; and, FIG. 4 is a top view of the music control device of FIG. 3. The broken lines in the Figures form no part of the claimed design.

1 Claim, 4 Drawing Sheets
